UNITED STATES PATENT OFFICE

GEORGE R. LANG, OF PITTSBURGH, PENNSYLVANIA

METHOD AND APPARATUS FOR MINING

Application filed October 5, 1927. Serial No. 224,150.

This invention relates to a method and apparatus for mining and more particularly to a method and apparatus for dislodging material to be mined from the mine working face. The invention is particularly applicable to use in coal mines of the type employing a substantially horizontal entry or working shaft and a substantially vertical working face, although it is by no means limited to a mine of this type. The invention will be described as applied in a present preferred embodiment to the mining of coal in a mine of the type above mentioned, it being understood that the invention may be otherwise variously embodied within the scope of the claims appended hereto.

In the mining of coal it is the usual practice to undercut the working face preparatory to "shooting" the coal, that is, before setting off the charge of powder or dynamite to loosen the coal in the working face. Such an undercut is usually made at the floor of the mine and is of a height of from four to six inches and a longitudinal depth of approximately six feet. The purpose of the undercut is to provide a space into which the "shot" coal may be projected when it is loosened by the explosion of the charge.

It has been found that when the coal to be mined is shot straight down upon the undercut, it is quite firmly packed against the floor of the mine, necessitating considerable loosening subsequent to the shot before the coal can be loaded into the conveyor or mine car. This entails additional labor and time and is consequently expensive.

According to the present invention I provide for the elimination of at least a substantial part of the loosening operation subsequent to shooting by inserting into the undercut a dislodging means onto which the shot coal is projected, so that after the charge has been exploded the dislodger may be withdrawn from the working face, pulling with it a quantity of the projected coal and serving to loosen the coal above so that practically no work other than the withdrawing of the dislodger is necessary subsequent to shooting before loading the coal into the conveyor or mine car. I further provide a flexible dis-

lodging means against which the shot coal is adapted to be projected and which may be withdrawn to progressively dislodge successive portions of the coal as it is drawn out. This is of advantage in that it is not necessary to withdraw the dislodger while the portion thereof upon which the tension is applied supports any great proportion of the weight of the projected coal. Means are also provided on the dislodger having a portion of considerable area as compared with that of the body of the dislodger for engaging with and dragging out lumps of coal. The dislodging means may be withdrawn by any suitable source of power, such as a mining machine provided with a rotatable element upon which the dislodger is wound.

The nature of the invention will be understood with reference to the accompanying drawings showing the present preferred embodiment, wherein

Fig. 1 is a horizontal cross section through a mine entry looking toward the floor thereof and showing my invention in use;

Fig. 2 is a vertical cross section through the mine entry shown in Fig. 1; and

Fig. 3 is a perspective view to enlarged scale of one form of dragging means adapted for use with the dislodger.

Referring more particularly to the drawings, there is shown a mine entry having a floor 2, side walls 3, ceiling 4 and working face 5. The usual undercut 6 is provided in the working face and is shown as being adjacent the mine floor, although such undercut may be provided at any desired height above the floor. Lying upon the base of the undercut and disposed in convolutions as shown in Fig. 1 is a dislodging means 7 illustrated as comprising a chain. The chain may be disposed in any desired manner in the undercut, it being shown in the drawings as in two series of convolutions, one on each side of the entry. The convolutions begin at the point where the dislodging means enters the working face and extend from that point rearwardly and transversely of the entry. The dislodger may comprise a cable, rope, or any other suitable means.

One or more holes 8 are drilled in the work-

100

ing face for the reception of the explosive charge 9. A track 10 is provided upon which a mine car 11 is adapted to be rolled into the entry for carrying out the coal. Any suitable means such as a loading machine 12 may be used to load the coal into the mine car. The loading machine as shown in the drawings rests directly upon the mine floor and is adapted to be moved to any desired position laterally or angularly in the entry.

10 The loading machine 12 is provided with a shaft 13 upon which is mounted for rotation a pair of drums 14. At the end of the loader disposed nearest the working face is 15 a pair of anti-friction bearing members 15. The dislodger 7 is adapted to be wound up upon either of the drums 14 and to engage the anti-friction bearing members when it is necessary that the dislodger pass around 20 a corner of the loading machine.

After the dislodger has been laid in place in the undercut as above described, the charge 9 is exploded and the coal in the working face projected downwardly against the dislodger. As above stated, such projection of the coal causes it to become rather tightly packed against the mine floor. The office of the dislodger is to remove and loosen the projected coal upon withdrawal thereof 25 from the working face. The dislodgers is withdrawn from beneath the projected coal by fastening its end to one of the drums 14 and causing rotation of the shaft 13 to wind up the dislodger on the drum. The coal nearest the mine floor will be drawn outwardly by the dislodger and toward the loading machine. That above, will fall down loosely in the space left by removal of the dislodger and the coal dragged out along with it, thus 30 leaving the coal at the working face in substantially loose condition and easy to handle.

In order to provide a considerable bearing surface on the dislodger for lumps of coal projected thereagainst, I provide a number 45 of dragging elements 16 each comprising a dragging head 17 and means 18 such as a hook for connecting the dragging element to the dislodger. These dragging elements are preferably flexibly connected to the dislodger so that when the dislodger assumes various 50 positions during its withdrawal the dragging elements will always dispose themselves so that the head 17 of each will be most effective for dragging out lumps of coal. The dragging elements may be omitted if desired.

I wish it distinctly understood that the dislodger 7 may be disposed in any desired manner in the undercut. There is an infinite number of variations which may be used in 60 placing the dislodger in order to cause the removal of the coal upon withdrawal thereof. For instance, it may be disposed in convolutions extending substantially transversely of the entry, in which case the coal is 65 dragged generally from one side toward the

other. I prefer, however, to dispose the dislodger in convolutions in a manner somewhat similar to that shown in Fig. 1 of the drawings so that the successive convolutions thereof will be effective for progressively dislodging successive portions of the projected coal as the dislodger is withdrawn. This is a feature of the method of the present invention, as by providing for the progressive dislodging of successive portions of the projected coal it is not necessary to pull the dislodger from beneath the entire weight of the coal in the working face at one time. Furthermore, after a layer of coal nearest the outside of the working face has been removed, 70 it will be much easier for the successive layers behind to be progressively removed. It will be noted that each successive portion of the coal removed by a convolution of the dislodger upon withdrawal thereof is substantially entirely removed from the working face before removal of the succeeding portion is begun.

It will be seen that substantially the whole of a layer of the projected coal in the working face may be withdrawn by suitably positioning the dislodger before shooting. This is of great advantage in increasing the tonnage of coal which can be mined in a given period of time, as only one withdrawing operation is necessary to remove an entire layer of coal, whereas with methods as heretofore practiced several operations were necessary.

The dislodger may be withdrawn by any suitable means and is not limited to withdrawal by a mining or loading machine. For instance, its end may be hitched onto a mine engine and the engine moved along the track away from the working face. Alternatively, a motor and pulley may be used. The use of the mining machine is particularly advantageous, however, in that when the coal is packed unusually tight and a force greater than usual is necessary to withdraw the dislodger, the end of the mining machine may be braced against a portion of the working face or against a side wall of the mine in order to provide for a pull greater than the greatest pull which the mining machine can withstand when merely resting on the floor. 110 The machine may be pulled up to the working face or against a side wall of the mine by initiating rotation of the shaft 13, but when it becomes lodged firmly against a portion of the mine it will be apparent that the machine can move no further and will consequently be braced so that the dislodger will be wound up upon the drum.

The word "flexible" as used in the claims is directed more particularly to the flexibility which is a property inherent in devices of the nature of a chain, rope, cable or the like as distinguished from flexibility brought about by connecting together a number of long rigid members such as trays or the like. 120 125 130

I thus provide a method of mining comprising projecting material to be mined against a dislodger and progressively dislodging successive portions of the projected material by withdrawing the dislodger. I further provide a mining apparatus comprising a flexible dislodger and means for withdrawing the dislodger from a mine working face.

I claim:

- 10 1. A method of mining, comprising undercutting, inserting a dislodger substantially universally flexible at relatively closely spaced points longitudinally thereof, in the undercut, projecting material to be mined 75
15 against the dislodger, and withdrawing the dislodger.
2. A method of mining, comprising projecting in a substantially vertical direction material to be mined against a dislodger, substantially universally flexible at relatively closely spaced points longitudinally thereof, and progressively dislodging successive portions of the projected material by withdrawing the dislodger.
- 20 3. A method of mining, comprising projecting material adjacent a mine working face against a dislodger comprising sections permanently connected together, and progressively completely dislodging successive portions of the projected material progressively removed from the working face by withdrawing the dislodger.
- 25 4. A method of mining, comprising inserting into a mine working face a dislodger substantially universally flexible at relatively closely spaced points longitudinally thereof, and progressively dislodging successive portions of the material to be mined by withdrawing the flexible dislodger.
- 30 5. A method of mining, comprising removing a portion of a mine working face, inserting into the space thus provided a dislodger substantially universally flexible at relatively closely spaced points longitudinally thereof, projecting material to be mined against the dislodger, and dislodging the projected material by withdrawing the flexible dislodger past the working face.
- 35 6. A method of mining, comprising projecting material to be mined against a dislodger substantially universally flexible at relatively closely spaced points longitudinally thereof, and dislodging the projected material by withdrawing the dislodger through such material.
- 40 7. A method of mining, comprising disposing a flexible dislodger in a curved path, projecting material to be mined thereagainst, and dislodging the projected material by withdrawing and thus straightening out the dislodger.
- 45 8. A method of mining, comprising disposing a dislodger in a curved path, projecting material to be mined thereagainst, and progressively dislodging successive portions
- of the projected material by withdrawing and straightening out the dislodger.
9. A method of mining, comprising disposing a flexible dislodger in convolutions, projecting material to be mined thereagainst, and successively straightening out the convolutions of the dislodger to progressively dislodge successive portions of the projected material.
10. A method of mining, comprising projecting material to be mined against a dislodger substantially universally flexible at relatively closely spaced points longitudinally thereof, and dislodging substantially the whole of a layer of such projected material by withdrawal of the dislodger.
11. A method of mining, comprising projecting in a substantially vertical direction against a dislodger disposed in a curve material to be mined, and dislodging substantially the whole of a horizontal layer of such projected material by withdrawal of the dislodger.
12. A method of mining, comprising projecting material to be mined against a dislodger substantially universally flexible at relatively closely spaced points longitudinally thereof, and withdrawing the dislodger through substantially the whole of a layer of such projected material.
13. Mining apparatus, comprising a dislodger substantially universally flexible at relatively closely spaced points longitudinally thereof, and means connected with one end only of the dislodger for withdrawing the dislodger from a mine working face.
14. Mining apparatus, comprising a relatively long, bendable substantially unitary non-endless dislodging element, and means for withdrawing such element from a mine working face.
15. The combination with a mining machine provided with winding means, of a flexible dislodging element adapted to be wound thereon.
16. A dislodging element comprising a flexible body portion substantially universally flexible at relatively closely spaced points longitudinally thereof, dragging elements on the body portion at intervals and operating means connected with one end only of the body portion.
17. A dislodging element comprising a chain free to be disposed in a desired curve, and dragging elements flexibly secured to the chain at intervals.
18. The combination of a relatively long dislodging element free to be disposed in a desired curve, dragging elements at intervals on the dislodging element, and means for winding up the dislodging element.
- In testimony whereof I have hereunto set my hand.
